S. B. WILBUR,
HEAT DISTRIBUTER OR PLATE,
APPLICATION FILED FEB 26, 1913.

1,114.087.

Patented Oct. 20, 1914.

Fig. 1.

FIG. 2.

UNITED STATES PATENT OFFICE.

STUART B. WILBUR, OF CHICAGO, ILLINOIS.

HEAT DISTRIBUTER OR PLATE.

1.114,087.

Specification of Letters Patent. Patented Oct. 20, 1914.

Application filed February 26, 1913. Serial No. 750,767.

To all whom it may concern:

Be it known that I, STUART B. WILBUR, a citizen of the United States, residing at Chicago, in the county of Cook and State of Illinois, have invented certain new and useful Improvements in a Heat Distributer or Plate, of which the following is a description.

My invention belongs to that general class of devices known as heat distributors or plates, and relates particularly to a device for use in cooking and preparing food, which food may be in suitable utensils, or may be placed upon the top of the plate, depending upon the article to be cooked, or it may be used for heating articles other than food. The device is particularly adapted to be used for baking purposes, in which case a cover may be placed over the same, the material to be baked being placed under the cover. When the device is so employed, food may be baked on the plate as satisfactorily as in an oven.

The invention has among its objects the production of a device of the kind described that is simple, convenient, durable, efficient, and satisfactory, and that may be manufactured and sold at small cost.

To this end my invention consists in the novel construction, arrangement and combination of parts herein shown and described, and more particularly pointed out in the claims.

In the drawings, wherein like reference characters indicate like or corresponding parts, Figure 1 is a top plan view of the device. Fig. 2 is a cross sectional view of the same, taken substantially on line 2, 2 of Fig. 1. Fig. 3 is a sectional view of a portion of a modified construction, and Fig. 4 is a top elevation of the same.

Referring to the drawings, my preferred distributer consists of a substantially flat top plate 1, which is provided with two or more series of holes or openings 2 and 3, arranged substantially as shown. The holes are of any preferred size, and there may be as many as desired, or as the space will permit. The top plate may be provided with ribs or ridges 4 and 5, and when the distributer is made of thin sheet metal, as shown in the drawings, the ribs or ridges may be formed by corrugating the plate. In the construction shown, the ribs extend proximate to the center of the plate, and a space is left as at 6, in which the name of

the manufacturer may be placed. The ribs are adapted to support and raise the cooking utensils slightly above the plate 1, and also tend to strengthen or stiffen the top 30 plate.

Arranged below the top plate is a plate 7, which is formed as shown most clearly in Fig. 2, or in an equivalent manner, and extended or flanged as at 8 about the periphery. This plate may be said to be convex, or concavo-convex, with the concave side toward the top plate, so as to form a heating chamber between the two. The extended flat flange 8 bears against or contacts with the under face of the plate 1, the same being of sufficient width to extend from the periphery of the top plate to a point between the openings or holes 2 and 3. Holes 9 are provided in the flange 8, the same being of 75 the same size and the same in number as the holes 2, so that when the two plates are secured together the holes 2 and 9 register.

The two plates may be secured together in any suitable manner, when the device is constructed of sheet metal. As shown, the top plate 1 is flanged downwardly at 11, and thence turned inwardly as at 12, to embrace a flange 10 on the lower plate. The flanges 10 and 11, when formed as shown, 36 are quite stiff or rigid, and serve to support the plate over a burner or flame. It is, of course, understood that the distributer may be constructed in any equivalent manner.

In Figs. 3 and 4, a slightly modified construction is shown, in which a top plate 13 is provided with slots 16, and a plate 14 secured below the plate 13, the same extending from and being secured to the top plate at points between the ends of the slots 16. The two plates may be secured together by rivets 18, or their equivalents. Ridges 17 are shown on the top plate similar to the other construction. This construction is similar in operation to the other construction, and an explanation of the operation of one will suffice for both. Assuming that the plate is positioned over a flame, a portion of the heat passes up through the holes 9 and 2, the same being directed to the holes by the convex face of the lower plate, and retained within the heater by the flanges 10 and 11. A portion of the heat is conducted through the lower plate 7, and heats the plate 1, the excess heat passing out through the holes 3. 110 In some cases a top or cover previously mentioned is not desirable. With it, however,

pies, cake, bread, biscuits, or meats, and the like, may be baked in the same manner as if in an oven, and toast may be made upon the plate, or flat irons heated thereon. A pan or pot will serve as a cover for baking purposes, or a special cover may be provided for the purpose.

Having thus described my invention, it is obvious that various immaterial modifications may be made in the same without departing from the spirit of my invention, hence I do not wish to be understood as limiting myself to the exact form, construction, arrangement, or combination of parts herein shown and described, or uses mentioned.

What I claim as new and desire to secure by Letters Patent is:—

1. A portable heat distributor for cooking utensils comprising a top plate having radiating ribs extending from a point adjacent the center thereof to a point adjacent the periphery thereof and also having a series of openings arranged in alternate relation with regard to said ribs adjacent the outer terminal thereof, a lower substantially semi-spherically-shaped plate secured at its upper edge to the under surface of the upper plate at a point beyond the ribs and holes, the lower plate being adapted to receive the direct action of the flame and separated from the upper plate by an unobstructed space, the upper plate having a depending annular supporting flange and the upper and lower plates having an annular series of registered holes at a point adjacent said flange, substantially as and for the purpose described.

2. A portable heat distributing member comprising an upper plate having a downwardly projecting edge flange extending therearound to constitute a support, a concavo-convex lower plate, the lowermost central portion thereof being substantially

parallel to the lower edge of said flange, and the upper outer edge being in contact with the upper plate adjacent the outer edge of the latter, the lower plate being separated from the upper plate by an unobstructed space and said lower plate being free from openings leading into said space, the upper plate having a series of openings communicating with said space between the plates, and an auxiliary series of openings therethrough adjacent the outer edge thereof in communication with the space between the under surface of the lower plate and the inner surface of said supporting flange.

3. A portable heat distributing member comprising an upper circular plate, having a downwardly projecting peripheral supporting flange, said upper plate having two concentrically arranged annular series of openings adjacent said peripheral flange, a lower plate having a concavo-convex central portion connecting with a flat peripheral portion at the upper edge thereof which said flat peripheral portion contacts with the under surface of the upper plate at a point outside of the inner series of openings therein and having a series of openings in registration with the outer series of openings of the upper plate, the concavo-convex portion of the lower plate being imperforate, a supporting flange projecting downwardly from said flat peripheral portion of the lower plate, and the peripheral flange of the upper plate having a bent portion overlying the lower edge of said supporting flange of the lower plate.

In testimony whereof, I have hereunto signed my name in the presence of two subscribing witnesses.

STUART B. WILBUR.
